DESIGN FOR A CARD ILLUMINATING FIXTURE

Alexander E. Blumenthal, Pittsburgh, Pa.

Application December 24, 1935, Serial No. 60,269

Term of patent 3½ years

To all whom it may concern:

Be it known that I, Alexander E. Blumenthal, a citizen of the United States, residing at Pittsburgh, in the county of Allegheny and State of Pennsylvania, have invented a new, original, and ornamental Design for Card Illuminating Fixtures, of which the following is a specification, reference being had to the accompanying drawing, constituting a part hereof.

Fig. 1 is a front view of the card illuminating fixture showing my new design, and

Fig. 2 is a side view thereof.

I claim:—

The ornamental design for a card illuminating fixture substantially as shown.

In testimony whereof, I have hereunto subscribed my name this 19th day of December, 1935.

ALEXANDER E. BLUMENTHAL.
